DESIGN FOR A SPECTACLE AND EYEGLASS CASE

Oswald B. Carson, Scarsdale, N. Y.

Application December 5, 1934, Serial No. 54,288

Term of patent 7 years

To all whom it may concern:

Be it known that I, Oswald B. Carson, a citizen of the United States and a resident of Scarsdale, in the county of Westchester and State of New York, have invented a new, original, and ornamental Design for a Spectacle and Eyeglass Case, of which the following is a specification, reference being had to the accompanying drawing, forming a part thereof, and in which:

Fig. 1 is a front elevation,

Fig. 2 is a perspective view showing front, end and top, and

Fig. 3 is an end elevation of a spectacle and eyeglass case embodying my new design.

I claim:

The ornamental design for a spectacle and eyeglass case, as shown.

OSWALD B. CARSON.
